HYDRAULIC BELT STRETCHER

Application filed February 24, 1928, Serial No. 256,695. Renewed May 31, 1932.

This invention relates to the stretching of drive belts and provides simple, effective and readily operable means for taking up slack or drawing a belt taut without the necessity 5 of removing it from the pulley.

The invention furthermore provides a device of the character aforesaid which may be easily manipulated by a single person for tightening the belt and holding the same securely 10 during the fastening of the ends, and removing it from the belt after the ends have been fastened.

The invention comprises a suitable frame, belt clamps, a cylinder, a piston in the cylinder, the clamps being connected with the piston and cylinder, respectively, for movement therewith, a pump for supplying liquid under pressure to the cylinder when stretching the belt, and means for releasing the pressure 20 after the belt has been stretched and fastened to admit of ready removal of the stretcher.

While the drawings illustrate a preferred embodiment of the invention it is to be understood that in adapting the means to meet specific needs and requirements the design may be varied and changes in the minor details of construction may be resorted to within the scope of the invention as claimed, without departing from the spirit thereof.

For a full understanding of the invention and the merits thereof, reference is to be had to the following description and the drawings hereto attached, in which,

35 Figure 1 is a top plan view of a belt stretcher embodying the invention, a portion being in section.

Figure 2 is a transverse section on the line 2—2 of Figure 1.

40 Figure 3 is an enlarged detail section on the line 3—3 of Figure 1.

Figure 4 is an enlarged detail section of a portion of the pump and the valved induction and eduction pipes connected therewith.

45 Figure 5 is an enlarged detail sectional view on the line 5—5 of Figure 1.

Corresponding and like parts are referred to in the following description and designated in the several views of the drawings by 50 like reference characters.

The frame of the device includes cylinders 1 and a plate 2 connecting the cylinders and forming supporting means for a tank 3 and pump 4. The cylinders 1 are of small bore and of some considerable length to provide ample allowance for stretching a belt. The plate 2 provides connecting means for the cylinders, which are disposed in parallel relation. Semi-circular depressions 5 are formed adjacent opposite ends of the plate 2 and provide seats in which the cylinders 1 are fitted. Cap plates 6 are bolted to the plate 2 and confine the cylinders 1 within the recesses 5.

The tank 3 is adapted to contain a quantity of liquid and may be secured to the plate 2 in any determinate way. The pump 4 is likewise secured to the plate 2 and is connected to the tank 3 by means of a pipe 7 in the length of which is located a check valve 8 to prevent return of the liquid from the pump to the tank. A pipe 9 connects with the pump 4 and is provided in its length with a check valve 10 which prevents return of the liquid from the cylinders to the pump. The pump piston is connected to an operating lever 11 which is connected to the plate 2 by means of a link 12. The pipe 13 connects the cylinders 1 and the eduction pipe 9 from the pump 4 is connected thereto. A pressure indicating gage 14 is connected with the pipe 13. A return pipe 15 connects the pipe 13 with the tank 3 and is provided in its length with a valve 16 which is closed when the cylinders 1 are under pressure and which is opened to relieve the pressure after the belt has been stretched and fastened to admit of ready removal of the stretcher.

Pistons 17 operating in the cylinders 1 are connected to rods 18 which operate through stuffing boxes 19 at the ends of the cylinders to which the pipe 13 is connected. A fitting 20 at the outer end of each of the rods 18 is connected by means of a clevis 21 to a belt clamp 22. A tip 23 is fitted to an end of each of the cylinders 1 and the pipe 13 is coupled thereto. A tip 24 is fitted to the opposite end of each of the cylinders 1 and is connected by means of a clevis 21 with a belt clamp 22. The pipe 13 is provided in its length with

a coil 25 to compensate for contraction and expansion to prevent straining the joint formed between said pipe and the tip 23.

The belt clamps 22 are of like formation, each comprising similar members which are connected at opposite ends by means of bolts 26. The clamps are formed with extensions 27 which are notched to receive the clevises 21 so as to prevent displacement thereof. The ends of the belt to be stretched are clamped between the members comprising the parts 22 and upon operating the pump 4 liquid is drawn from the tank 3 into the pump cylinder through the eduction pipe 7 and is forced from the pump cylinder through the eduction pipe 9 into the pipe 13, thence into the cylinders 1 and causing the pistons 17 to move inwardly therein. This action draws the clamps 22 together and effects a stretching of the belt which is held during the fastening of the ends. After the belt has been tightened and fastened the valve 16 is opened, thereby relieving the pressure which passes from the cylinders through the pipes 13 and 15 back into the tank 3. The construction admits of the device being manipulated by one person, both when placing the stretcher in position and when removing it from the belt after the latter has been stretched and fastened. The belt, when stretched, is held until fastened, because the pressure within the cylinders is maintained until relieved by opening of the valve 16.

Having thus described the invention, we claim:

An apparatus for the purpose set forth comprising a plate having longitudinal depressions near its side edges, cylinders seated in said depressions, caps secured on the plate over the cylinders whereby the cylinders will be supported and maintained in parallel relation by and at opposite sides of the plate, pistons in the cylinders, a rod extending from each piston through one end of the respective cylinder, work-engaging means connecting the outer ends of said rods, work-engaging means connecting the ends of the cylinders remote from the outer ends of the rods, a tank on the plate, a pump on the plate connected with the tank, a transverse pipe connected with the outlet of the pump and having its ends connected with the respective cylinders, said pipe having a coil formed therein between its ends, and a valve connection between the transverse pipe and the tank.

In testimony whereof we affix our signatures.
